UNITED STATES PATENT OFFICE.

JOHN RUSSO, OF FITCHBURG, MASSACHUSETTS.

SECTIONAL TRACK.

1,241,769.

Specification of Letters Patent.

Patented Oct. 2, 1917.

Application filed August 6, 1917. Serial No. 184,621.

To all whom it may concern:

Be it known that I, JOHN RUSSO, a subject of the King of Italy, residing at Fitchburg, in the county of Worcester and State of Massachusetts, have invented a new and useful Sectional Track; of which the following is a specification.

This invention relates to a sectional track possessing many features of novelty and utility. The construction is more particularly adapted for temporary use and light loads although not limited thereto.

It is the general object of my invention to provide a sectional track construction, in which new sections can be laid mechanically and without resort to manual labor to advance or operatively position the same.

With this general object in view, important features of my invention relate to 20 means for mechanically advancing new sections over the sections already laid; to devices for inverting and bringing each new section into operative position; to driving mechanism on each section adapted to 25 assume driving relation with the mechanism of the prior sections as it moves into operative position; to devices for holding the sections in operative relation to each other; and to other devices, arrangements and combinations of parts which will be hereinafter described and more particularly pointed out in the appended claims.

A preferred form of my invention is shown in the drawings in which—

35 Figure 1 is a front elevation of several sections of my improved track;

Fig. 2 is a detailed side elevation of a portion of the driving and supporting mechanism, looking in the direction of the arrow 2 in Fig. 1;

Fig. 3 is a plan view of two successive sections;

Fig. 4 is a detailed sectional elevation taken along the line 4-4 of Fig. 3; and

45 Fig. 5 is a detailed elevation of the parts which engage the conveyer chains, looking in the direction of the arrow 5 in Fig. 1.

Referring to Fig. 1, I have shown two sections operatively positioned and a third section in inverted position for movement along the previously positioned sections. The three sections may be conveniently designated, A, B and C. Each section, as A, is provided with a frame 10 preferably formed 50 as a trapezoid, in which the upwardly in-

clined members 10^a and 10^b are of slightly unequal lengths. This produces a narrowing of the rear portion of each section; and permits the sections to adapt themselves somewhat more readily to uneven ground. 60 After a new section is in operative position, suitable blocking may be placed under one or more of the cross-pieces 11 to preserve the alignment of the section.

A pair of conveyer chains 13 (Fig. 3) 65 extend longitudinally of each section which may be of any desired length. At their rear ends the chains 13 are supported and driven by sprockets 14 mounted on short shafts 15 extending through bearings in the 70 end frame members 10^b. The shafts 15 are provided at their outer ends with additional sprockets 16 driven by transmission chains 18 to be described. In the case of the first section A, the transmission chains 18^a may 75 be driven from a suitable motor M or from any other convenient source of power.

At the right hand end of each section the chains 13 pass over sprockets 19 fixed on short shafts 20 having bearings in the end 80 frame member 10^a. Said shafts are provided at their outer ends with gears 21, meshing with gears 22 (Fig. 1) mounted on arms 23 pivoted to swing about the axis of the shafts 20. Springs 24 move the arms 23 85 yielding upward.

Each end frame member 10^a is provided with a heavy hook-shaped member 25 for a purpose to be described. There is also provided a weighted engaging member or link 90 26 (Fig. 1) pivotally mounted in a slot in an upper corner of the frame 10.

Intermediate chains 30 (Figs. 3 and 4) are provided at the rear end of each section except the first, these chains being supported and driven by additional sprockets 31 on the short shafts 15, and by guide pulleys or sprockets 32 mounted at the end of arms 33 fixed in rearwardly-extending position on the frame members 10^b. As the successive sections are operatively positioned the intermediate chains 30 will bridge over the gaps or openings between the successive chains 13, thus providing a continuous conveyer the whole length of the track! 100

I will now describe the driving connections between the successive chains 13. Each chain 18, previously described, is driven by a sprocket 35 mounted on a stud 36 (Figs. 1 and 2) fixed in an upper rear corner of 110

the frame 10. A second sprocket 37 (Fig. 3), also mounted on the stud 36 and fast to the sprocket 35, carries a chain 38 (Figs. 1 and 2) which extends around another driving sprocket 39. Each sprocket 39 has a gear 40 fixed thereto and is rotatable on a stud 41 secured in the end of an arm 42 pivoted to swing about the axis of the stud 36.

10 The gear 40 is positioned for engagement by the gear 22, previously described, such engagement being made as the section is moved downward to operative position. The arms 42 are provided with rolls 42^a loose on the studs 41 and upon which the new track section is supported as it is moved along the preceding sections.

15 When the new section is to be advanced along the section previously laid, the arms 42 are swung to the position shown in section C, of Fig. 1, in which position they are retained by swinging latches 43 which engage the studs 41. Hook-shaped links 44 are also pivoted to the frame 10 in the corners adjacent the latches 43, said hooks being adapted to engage the weighted links 26 above mentioned as each new section reaches the end of the section last laid.

20 The parts are moved along the previously laid track by a brace member 50, which may be hinged to a cross-piece 11 or to any other convenient point on the frame 10. The brace 50 is somewhat narrower than the distance between the conveyer chains 13 and 25 is provided with laterally projecting arms 51 adapted to engage spurs or lugs 13^a and 30^a on the chains 13 and 30 respectively, by which means the brace 50 is effective to advance the inverted track section to which 30 it is attached.

25 The arms 51 are arranged to fold inward so as to permit them to pass downward between the chains 13 as the track section completes its movement to operative position. For this purpose the arms 51 are pivoted at 52 to the brace 50, and the inner ends of the arms 51 are connected by links 53 to a rod 54 having a loop at its upper end through which a locking pin 55 normally extends. A cord 56 is secured at one 40 end to the pin 55 and at the other end to the cross-piece 11, in such position that the cord will be tensioned as the brace 50 swings to inoperative position, thus withdrawing the pin 55 and permitting the arms 51 to move to inoperative position, under the influence of springs 57. Guides 60 are provided on the inner side of the frame members to retain the advancing frame section in correct lateral position upon the track previously laid.

60 Having described the construction of my improved sectional track, I will now describe the operation. Assuming that sections A and B have been previously laid,

and that the conveyer chains 13 of section A are driven from a suitable motor M, these chains will drive the conveyer chains 13 of the section B through the connecting mechanism described comprising for each chain 13 the spur gears 21, 22 and 40, the sprocket 39 and chain 38, the sprocket 37 and 35 and chain 18, and the sprockets 16 and 14, the latter driving one of the conveyer chains 13 of section B. At the same time, each chain 18 drives an intermediate chain 30 through the shaft 15 and sprocket 31, thus providing for the movement of the brace 50 from one conveyer chain 13 to the next succeeding chain 13. As the section C is advanced by its brace 50, it rolls along upon its roll 42^a with its rear portion positioned laterally by the guides 60.

65 As the section C approaches the end of the section B, its rolls 42^a pass down along the inclined forward end 10^a of the section B, and at the same time the latches 43 are released by engagement with studs 43^a on the frame of section B, (Fig. 3). Such movement also causes the hooks 44 on section C to engage the weighted links 26 on the section B, thus connecting the upper edges of the sections together. The studs 41 which support the rolls 42^a, the sprockets 39 and the spur gears 40 are then engaged by the hooks 25, thus bringing the spur gears 40 into position for engagement by the swinging spur gears 22, which latter gears are forced downwardly against the tension of the springs 24 to the position shown in Fig. 1, and provide driving connection between the two sections. The arms 33 fixed to the frame of the section C are moved therewith to the position shown in Fig. 4, with the intermediate chains 30 bridging over the spaces between the successive conveyer chains 13. As the section C is turned over, the brace 50 swings down between the chains 13, and eventually occupies the position indicated in dotted lines 110 in the section B.

70 My invention permits a light or temporary track to be laid with great ease and rapidity, it being merely necessary to place additional sections upon some portions of the track already laid, and to swing the brace 50 thereof into a position in which its arms 51 engage the lugs 13^a on the conveyer chains 13. The new section will be automatically advanced to the end of the track 120 previously laid, and will then be turned over into operative position, without further attention. In this way the track may be laid with great rapidity and with a very small amount of manual labor, such labor being 125 used merely to place new sections in position for movement along the track previously laid.

75 Having thus described my invention, it will be evident that changes and modifica- 130

tions can be made therein by those skilled in the art without departing from the spirit and scope thereof as set forth in the claims, and I do not wish to be otherwise limited to the details herein disclosed, but what I claim is:—

1. A track comprising successive sections, each of said sections having driving mechanism mounted therein effective to move additional sections thereover.

2. A sectional track construction comprising a plurality of sections movable separately to operative position, driving mechanism therein, and means for automatically establishing driving relation between successive sections as each new section reaches operative position.

3. A sectional track construction comprising a plurality of successive sections forming a track, means to support a new section thereon, means to advance said section along said track, and means to operatively position said new section at the end of the section last laid.

25 4. A track comprising successive sections, each of said sections being provided with driving mechanism effective to move additional new sections thereover, and the mechanism of each new section automatically assuming driving relationship with the mechanism of the last preceding section as each new section is moved into operative position.

35 5. A track comprising successive sections, each section having conveyer chains disposed lengthwise thereof, driving connections between the conveyer chains of adjacent sections, and means to drive the entire series of conveyer chains.

40 6. A track comprising successive sections, means to move each new section in inverted position along the preceding sections, and means to reverse said new section into operative position at the end of the section last laid.

45 7. A track comprising successive sections, means to support a new section in inverted position on the preceding sections, a conveyer to move said new section along the track, and connections from said conveyer to said new section, adapted to reverse the section into operative position when it reaches the end of the section last laid.

50 8. In a sectional track construction, a plurality of sections, means to support a new section in inverted position on the sections previously laid, conveying chains, and means on said inverted section engaging said

chains whereby said section may be advanced.

60 9. A track comprising successive sections, means to support a new section in inverted position on the preceding sections, a conveyer to move said new section along the track, link members mounted in pairs at adjacent ends of successive sections, and effective to engage when an inverted section reaches the end of the section last laid, said members thereafter forming connections to pivots in said last laid section about which said new section is reversed, and means to reverse said new section to operative position.

70 10. In a sectional track construction, a plurality of sections, means to support a new section in inverted position on the sections previously laid, conveying chains, and means on said inverted section engaging said chains whereby said section may be advanced, said means including a brace pivoted to said new section and having laterally projecting chain-engaging arms at its free end, means to hold said arms in operative position, and means to release said arms as said new section is turned to operative position.

75 11. A sectional track construction comprising a plurality of sections movable separately to operative position, driving mechanism thereon, and provision for automatically establishing driving relation between successive sections as each new section reaches operative position, said provision including coöperating gears mounted on arms pivoted to the successive sections, and means to force said gears yieldingly into driving relation.

95 12. A sectional track construction comprising successive sections, each pair of adjacent sections having coöperating link members at their adjacent ends, effective to engage as each new section approaches operative position, and to thereafter form intermediate tread sections between successive track sections.

100 13. A sectional track construction comprising a plurality of successive sections forming a track, means to support a new section thereon, conveying chains to advance said section along said track, means to operatively position said new section at the end of the section last laid and intermediate chains at the rear end of each section, effective to bridge the space between successive conveyer chains.

In testimony whereof I have hereunto affixed my signature

JOHN RUSSO.
